TYPEWRITING MACHINE

William F. Helmond, Clinton, Conn., assignor to
 Underwood Elliott Fisher Company, New York,
 N. Y., a corporation of Delaware

Application March 21, 1941, Serial No. 284,530

8 Claims. (Cl. 197—138)

This invention relates to paper-feeding means for typewriting machines, for feeding, guiding and holding a work sheet at the front of the typewriter platen above the typing line.

In front strike typewriters, the paper-feed bail is arranged to be movable from platen contact to facilitate the insertion of a work sheet and the making of erasures. It is highly desirable to have the bail displaceable in a forward direction from its normal position to a position well away from the platen so that a wide opening is afforded into which the top end of the paper may be received as it is fed around the platen. When the paper is thus installed, the operator, in a carefree manner, may restore the bail to its normal position. Thus, the operator is relieved of the necessity of threading the paper under the bail, as would be the case with bails which are shiftable to positions upwardly or rearwardly of the platen. It is also desirable that the bail, while being restored, approach the platen in a direction generally tangential thereto, thus to eliminate any tendency to create a bulge of the paper at the typing line as has existed with some prior overhead bail mechanisms.

Front bails have been proposed which have the advantages of forward displacement and tangential restoration, but these advantages in such proposed arrangements have been offset by objectionable, costly and bulky structure which interferes with the proper placement and operation of other essential mechanisms on the typewriter carriage. While these objections in part are obviated in certain bail structures characterized by a fixed pivotal mounting for the bail, such structures, in order to afford the advantages of forward displacement and tangential return, require arrangement of the bail pivots well above and forwardly of the platen, necessitating supports projecting objectionably from the normal carriage structure.

The present invention has among its objects the provision of a paper-feeding means having a bail which is adapted to be displaced forwardly of and well away from the platen and restored in a path generally tangential to the platen, and which is a simple, compact, inexpensive and reliably operative structure.

Another object is to provide a front bail mounting presenting an extensible and collapsible structure completely arranged substantially within the compass of the normal carriage structure and entirely forward of and above the platen axis, so that the arrangement and operation of

other conventional mechanisms of the platen carriage are not encumbered.

A further object is to provide a mechanism in which the bail moves constantly in parallelism with the platen and may be operated by a light finger touch for displacement or restoration, thus enabling the use of the mechanism with extra long, as well as the usual length, platen carriages.

A further object is to provide paper-feed mechanism, the bail of which, although having its mounting entirely forward of the platen, approaches the platen tangentially while being restored, and on engaging the platen, moves around same a suitable extent to assure the elimination of any bulging of the paper at the typing line; another object being to provide a bail of this character which will readily accommodate various thicknesses of manifold work pack, holding same snugly against the platen.

A further object is to provide a paper-feed bail mechanism, the associated spring of which urges the bail to either its normal or inactive positions with a relatively light yet ample tension, to permit operation of the bail with a light finger touch; the coaction of the parts at paper-feed position being such that the spring imparts an additional force to the bail, so translated as to press the bail radially against the platen and with ample yield to accommodate manifold sheets.

Other objects and advantages will hereinafter appear.

In the drawings,

Figure 1 is a front elevational view of a typewriter carriage unit showing the bail mechanism of the invention, with the bail rod in extended position away from the platen.

Figure 2 is a transverse sectional view through the mechanism, taken on line 2—2 of Figure 1, with the bail rod in corresponding position.

Figure 3 is a view similar to Figure 2 but showing the bail rod in normal position with the feed rolls against the platen and in an intermediate position.

Figure 4 is an end elevation of the bail mechanism in position similar to that shown in Figure 3, illustrating the action of the mechanism in accommodating manifold work sheets.

Figure 5 is an end elevation, illustrating a modified form of the invention, the bail being shown in extended and intermediate positions, and

Figure 6 is a view similar to Figure 4 but illustrating the modified form of the invention.

The usual cylindrical platen 8 shown, is

mounted for rotation on end members 9 of the platen carriage and cooperates with the usual bottom feed rolls 13 to feed a work sheet in the well-known manner. The platen mounting shown provides for removal of the platen for the usual purposes, the overhead bail mechanism of the invention being particularly suited for association with removable platen arrangements in that the bail mounting may be entirely forward of the platen and thus will not encumber the platen mounting affording removal. Each carriage end member 9 includes a bracket 11 on which the supporting devices of the bail mechanism are mounted.

The bail rod indicated at 12 is preferably square in cross section to provide surfaces for letter-space scales and which may accommodate feed rolls 13 of the character shown and described in my Patent No. 2,163,944, dated June 27, 1939.

At each end of the bail rod 12 is rigidly secured a lever arm 14, each arm having formed at one end a channel-shaped lug to which the bail rod is secured. The other end of each lever arm or bail end member 14 provides a pivot 15 by which the lever arm is articulated to a straight link 16 pivotally mounted on the bracket 11 by a stud 17. An angle link 18 is connected to each lever arm 14 intermediate the bail rod 12 and the pivot 15 by a pivot 20 and these angle links are pivotally mounted to the brackets 11 by studs 21 carried on the brackets and extending through elongate slots 22 in the links. When the bail rod 12 is brought to extended position away from the platen, as shown in Figures 1 and 2, the angle links 18 come to rest against stop pins 23 on the brackets 11. Springs 24 are arranged to act upon the straight links so as to urge same to rotate about their studs 17 in a counterclockwise direction as viewed in Figure 2. The spring 24 is preferably formed of a coil of wire embracing the stud 17, the end portions of the wire being oppositely extended to engage the link 16 and the bracket 11 respectively.

The bail rod 12 and its end arms or members 14 constitute a rigid bail or rectangular frame of which the rod 12 forms a longitudinal side, and the arms 14 form the ends. The bail rod, in addition to providing support for the feed rolls 8, functions as a torsional or equalizing member of the frame or bail and thus causes each of the arms 14 and, therefore, the associated links, to move correspondingly, with the result that the bail rod 12 is maintained in constant parallelism with the platen axis.

It may be here noted that the bail 14-12-14, in moving between positions at or well away from the platen, moves fore and aft of the typewriter through a perpendicular plane intersecting the axis 15 of the bail. The extensible and collapsible structure comprising the bail and supporting linkage controls movement of the bail toward the platen in a rearwardly swinging manner, while the bail is given a turning movement and its cross piece or bail rod 12 is constrained to take a substantially straight-line path toward the platen. The spring 24 resists the swinging movement of the bail until the bail has turned a predetermined extent and thereafter assists the swinging movement of the bail, tending to collapse the linkage and thus urge the bail rod toward the platen.

It will be seen that the bail mechanism at each end presents a three-arm linkage comprising the link 16, arm portion 25 and link 18, the arm por-

tion 25 forming an intermediate or connecting member of the linkage. The coaction of the linkage elements however may be more readily understood by considering the mechanism as including first, the two-arm linkage 16, 25, and second, the two-arm linkage 25, 18, both linkages having as a common element, the linkage member or arm portion 25 of the bail 12, 16.

When manual pressure is applied to the bail rod 12 in its extended position, Figure 2, the two-arm linkage 16, 25 is being folded, during which the pivot 15 is moved in a clockwise direction about the stud 17 against the force of spring 24. The manual effort on the bail rod is continued until the linkage assumes a "dead center" position shown in dotted outline in Figure 2. This "dead center" position is assumed when the second linkage 25, 18 is in straight condition, that is, when the pivot 20 is on a straight line with the axes of pivot 15 and stud 21. When the linkage is moved just beyond "dead center" position, the force of spring 24 on the linkage mechanism tends to fold linkage 25, 18 and thus urges the bail rod 12 toward the platen to the Figure 3 position without further manual effort. It will, therefore, be seen that the spring 24, although acting in a constant direction with respect to the link 16 and its center of rotation 17, has the effect of an overthrow spring because of the coaction of the elements of the three-arm linkage in moving from one side to the other of the "dead center" position shown. To move the bail rod 12 from normal to extended positions, or vice versa, manual effort need be applied only to carry the mechanism just beyond "dead center" position, after which the spring 24 will actuate the mechanism to carry the bail rod to the desired position.

In the extended position, Figure 2, the linkage 16, 25 approaches a straight condition and the spring 24 tends to further straighten this linkage, thus holding the bail at the extended position determined by the angle link 18 engaging the stop pin 23. In the normal position of the bail rod, Figure 3, the linkage 16, 25 is folded and the spring 24, through the guiding action of link 18 with the linkage elements 16, 25, brings the bail rod 12 in a substantially straight path toward the platen, approaching the platen in a direction generally tangential to its periphery. As the bail rod approaches the platen, the feed rolls 13 come into engagement with the platen periphery or the work sheet thereon and roll over the platen for a short distance in a wiping action that tends to wrap the work sheet around the platen and thus eliminates any bulging of the sheet at the printing line. The pivot 23 of the linkage carries a pin 26 which extends outwardly from the linkage to overlie the bracket 11 for co-operation with a shoulder 27 thereon, as shown in Figures 1 and 4. The normal position of the bail rod with the feed rolls 13 engaging the platen is determined by engagement of the pin 26 with the shoulder 27. This shoulder is so directed in relation to the platen axis that the pin 26, under influence of spring 24, is cammed in such direction as to press the feed rolls toward the platen in a direction generally radially there-of.

The limited play of the linkage, afforded by the elongate slot 22, allows movement of the feed rolls radially away from the platen to accommodate manifold sheets. That is, the feed rolls may move toward the position thereof shown in phantom in Figure 4, at which a work pack of

material thickness may be accommodated. During this action, the link 18 moves endwise on the stud 21 within the limits of the slot 22 and the pin 26 slides along the shoulder 27 correspondingly, all against the force of spring 24 which, acting through the linkage, presses the feed rolls 13 constantly toward the platen.

It will be observed that the pivots 15 at each end of the frame or bail 12, 14 define a longitudinal axis on which the frame or bail is swingable and movable, in a sense, edgewise upwardly and downwardly, it being apparent that the link 16 constitutes mounting means by which such movement of the frame is afforded. It will also be observed that the pivots 20 at each end of the frame form a longitudinal axis adjacent the bail rod 12, which axis is caused, by the mounting means embodied in the link 14, to move in a path generally transverse to said edgewise or up-and-down movement of the frame. The two links 16, 18 thus form mounting means for the frame or bail 12, 14 by which the latter is capable of a combined swinging and turning movement about axes longitudinal with respect to the frame. The effect of the spring 24 is that of urging the frame 12, 14 against said upward movement bodily, with the result that the bail rod 12 is caused to be yieldably held in either position at or away from the platen, depending upon which side of the "dead center" position the axis 20 of the bail is disposed.

The modified form of the invention, illustrated in Figures 5 and 6, presents a linkage mechanism and bail arrangement like that described for the first form. The principal difference in the modified form resides in the type and arrangement of the spring means acting upon the linkage to carry the bail rod to either its normal or extended positions. In place of the torsion spring 24, in the first form, a tension spring 28 is provided, one end of which is anchored on bracket 11 by a stud 29, the other end being connected to the linkage at the pivot 15. In urging the bail rod to either position, spring 28 acts upon the linkage in substantially the same manner as does the torsion spring 24, namely tending to constantly resist movement of the bail bodily up. To effect this operation, it is necessary that the point of anchorage 29 of the spring be located in a particular relation to the axes of pivots 15 and 17 with the linkage in "dead center" position as shown in dotted outline in Figure 5. Accordingly, the anchorage point 29 should be located on a straight line projected from the pivot point 15 with the linkage at "dead center," said line passing slightly below or to the left of pivot point 17, as viewed in Figure 5. In this way, spring 28 always exerts a force on the pivot 15 tending to turn the link 16 in a constant direction.

As will be apparent in Figure 6, the arrangement of spring 28 has the additional effect of urging the bail rod 12 directly toward the platen when the linkage is folded to normal position. In this condition, the pin 26, being engaged with the shoulder 27, also engages the spring 28 intermediate its ends causing the spring to be flexed longitudinally out of its normal straight condition. The force of spring 28 is thus translated directly to the pin 26 in such manner that the feed rolls 13 are pressed toward the platen by an extra force in addition to that imparted to the feed rolls by the spring tension acting upon the linkage at pivot 15. The spring anchorage 29 should, of course be located also in reference to

the axes of pivots 15 and 20 in the normal condition of the linkage, so that the spring is flexed by pin 26, as described.

Although in this application, there is specifically described, two embodiments which the invention may assume in practice, it will be understood that same are shown for the purposes of illustration, and that the invention may be modified and embodied in various other forms without departing from its spirit or the scope of the appended claims.

What is claimed is:

1. In combination, a typewriter carriage, a platen thereon, a paper-guiding bail having a crosspiece and opposite end members, and means for guiding the crosspiece toward and away from the platen, comprising devices mounting the bail on the carriage, having provision for effecting a swinging movement of the bail combined with a turning movement on an axis intermediate the extremities of the bail end members as the crosspiece is moved toward the platen and simultaneously constraining the crosspiece to take a substantially straight-line course toward the platen.

2. In combination, a typewriter carriage, a platen thereon, a paper-guiding bail having a crosspiece and opposite end members, means for guiding the crosspiece toward and away from the platen, comprising devices mounting the bail on the carriage, having provision for effecting a combined swinging and turning movement of the bail as the crosspiece is moved toward the platen and simultaneously constraining the crosspiece to take a substantially straight line course toward the platen, and spring means resisting the bail in its swinging movement until the bail has turned a predetermined extent and thereafter assisting the bail in its swinging movement until the crosspiece is at the platen.

3. In combination, a typewriter carriage, a platen thereon, a paper-guiding bail having a crosspiece and opposite-end members, means for guiding the crosspiece toward and away from the platen, comprising devices mounting the bail on the carriage, having provision for effecting a combined swinging and turning movement of the bail as the crosspiece is moved toward the platen and simultaneously constraining the crosspiece to take a substantially straight line course toward the platen, spring means resisting the bail in its swinging movement until the bail has turned a predetermined extent and thereafter assisting the bail in its swinging movement until the crosspiece is at the platen, and means for stopping the bail in its movement away from the platen, while the bail is maintained under the influence of the spring means.

4. In combination, a typewriter carriage, a platen thereon, and an extensible and collapsible structure comprising a crosspiece having end arms thereon providing an overhead bail for the platen, and links and connections for connecting the bail by its end arms to the carriage; said links and connections having provision for controlling movement of the bail toward the platen in a swinging manner and simultaneously turning it on an axis intermediate the extremities of the bail end-arms meanwhile the bail crosspiece is constrained to take a substantially straight line path toward the platen, and spring means resisting the first part of said controlled movement of the bail, and assisting the last part of said controlled movement to collapse the

structure and urge the crosspiece toward the platen.

5. In a typewriting machine having a platen and a carriage; a paper-guiding bail including end arms and a rod connecting the arms at corresponding ends, means mounting said bail for movement on the carriage to position the bail rod at or away from the platen, said mounting means including a link at each bail end pivoted on the carriage and to the bail arm at a point remote from the bail rod, and a second link at each bail end pivoted on the carriage and to the bail at a point intermediate the bail rod and the first said link.

6. In a typewriting machine having a platen and a platen carriage; a paper-guiding bail including end arms and a connecting bail rod, means mounting said bail for movement to guide the bail rod in a normal path to or away from the platen, including a link at each bail end pivoted on the carriage and to the bail arm adjacent its end for pivotal and edgewise movement of the bail, spring means yieldably resisting said edgewise bail movement in one direction, a second link at each bail end pivoted on the carriage and to the bail at a point adjacent the bail rod to guide said point in a normal lineal path generally transverse to the edgewise movement of the bail, and a pin movable with the bail in a normal path and engageable with a stop on the carriage to arrest the bail rod adjacent the platen, said stop extending transversely to the normal path of said pin and said second link having provision for limited endwise movement to afford bail rod movement in a direction transverse to its normal path.

7. In a typewriting machine having a platen and a carriage; a paper-guiding bail including end arms and a connecting bail rod, means mounting said bail for movement to guide the bail rod in a normal path to or away from the platen, including a link at each bail end pivoted on the carriage and to the bail arm adjacent its end for pivotal and edgewise movement of the bail, a second link at each bail end pivoted on

the carriage and to the bail at a point adjacent the bail rod to guide said point in a normal lineal path generally transverse to the edgewise movement of the bail, means for limiting the extent of bail rocking movement to arrest said bail rod in positions at or away from the platen, said mounting means and limiting means having provision for limited movement of the bail rod in a direction transverse to its normal path, and spring means for resisting the edgewise bail movement and movement of the bail rod transverse to its normal path, said mounting means having a part engageable with said spring means, with the bail rod adjacent the platen, to further resist movement of the bail rod in one direction transverse to its normal path.

8. In a typewriting machine having a platen and a platen carriage, a paper-guiding bail including end arms and a connecting bail rod, means mounting said bail for movement to guide the bail rod in a normal path to or away from the platen, including a link at each bail end pivoted on the carriage and to the bail arm adjacent its end for pivotal and edgewise movement of the bail, a tension spring interposed between the carriage and said mounting means to resist said edgewise bail movement in one direction, a second link at each bail end pivoted on the carriage and to the bail at a point adjacent the bail rod to guide said point in a normal lineal path generally transverse to the edgewise movement of the bail, and a pin movable with the bail in a normal path and engageable with a stop on the carriage to arrest the bail rod adjacent the platen, said stop extending transversely to the normal path of said pin and said second link having provision for limited endwise movement to afford bail rod movement in a direction transverse to its normal path, said pin being adapted to engage said spring with the bail rod positioned adjacent the platen, whereby said spring directly resists movement of the bail rod in one direction transverse to its normal path.
